UNITED STATES PATENT OFFICE

NELL FULTON, OF NEW YORK, N. Y.

COMB CLEANER

Application filed April 20, 1929. Serial No. 356,667.

My invention relates to comb cleaners and it has for its object the provision of a neat, serviceable and attractive holding device for the webbing which is used for cleaning combs.

5 Another of my objects is the provision of an all-wire frame for holding the webbing under tension.

Still another object of the invention is the provision of a holding member for the cleaning web, the holding member being so arranged that the web will be oblique to the stroke of the comb when in use.

Having in view these objects and others which will be pointed out in the following 15 description, I will now refer to the drawings, in which

Figure 1 is a view in perspective showing one form of my comb cleaner.

Figure 2 is a plan view showing another 20 form of the comb cleaner.

The present invention is in the nature of an improvement on the comb cleaner which I have shown and described in my copending application Serial No. 324,541, filed December 7, 1928.

The webbing 10 consists of a plurality of strands having woven portions at the opposite extremities, the woven portions being stitched to form loops at the ends of the 30 webbing. In the Figure 1 construction I employ a single piece of stiff wire bent into the form shown. The handle portion 11 is bent to form a loop to be conveniently grasped by the hand. The two portions of wire at 35 the loop are parallel to each other for a slight distance at 12 where they are preferably welded or otherwise secured together. The portion 13 is inclined in an upward and rearward direction and the portion 14 is inclined upwardly, rearwardly, and laterally. The portion 15 is horizontal with a slight rearward inclination toward its free end, the free end terminating in a rearwardly and laterally bent portion 16.

45 The portion 17 is a continuation of the handle member 11 and it is horizontal, continuing into a portion 18 which is forwardly and upwardly inclined with respect to both the handle and the portion 17. The portion 50 19 has a forward, upward, and lateral in-

clination and it terminates in the horizontal portion 20 which is forwardly inclined toward its free extremity.

The portions 13 and 18 are complementary, the one being inclined rearwardly and the other forwardly at a substantially equal angle. Likewise the portions 14 and 19, are complementary since their inclinations are precisely the opposite of each other. The holding portion 15 is substantially parallel to the holding portion 20, their inclinations being opposite.

The entire frame has considerable resiliency although it is made from very stiff wire, and when the webbing 10 is attached to the portions 15 and 20, as shown in Figure 1, it is held under considerable tension. The webbing is first slipped with its loop over the free extremity of the holding member 15 and pressure is then applied between the ends of the frame in order to slip the opposite end loop of the webbing over the holding portion 20. This tension may be adjusted by altering the angles of the portions 13 and 18 with respect to the portion 17.

Since the webbing is secured to the holding members 15 and 20 which are both biased outwardly but which are parallel to each other, it is obvious that the parallel strands of the webbing will be inclined with reference to the longitudinal axis of the webbing so that the normal stroke of the comb through the strands of the webbing will cause these strands to bear with greater force against one edge of the teeth of the comb to thus more effectually clean that edge of the teeth. By simply reversing the comb, the opposite edge of the teeth may be cleaned in a like manner.

In the Figure 2 construction the webbing 10 is precisely the same as the webbing 10 in the Figure 1 construction. As a holding means I provide a pair of supports for the ends of the webbing. Each of these supports consists of a single piece of wire having a portion 21 for engaging a loop of the webbing and terminating in an incurved piece 22 at its free extremity. The wire is looped back upon itself at 23 and then formed into a closed loop 24 which is sufficiently large to receive a finger. In this case also the web-

bing 10 is held obliquely to the longitudinal axis of the webbing since the holding portions 21 are biased outwardly and since the tension on the webbing is normally exerted in a direction which is oblique to the longitudinal axis of the webbing.

The Figure 2 device is designed to be secured at either end to a nail or hook or other convenient support passing through a loop 24. The other loop is then grasped by the finger and the webbing is held under tension while in use. The path of the comb will be slightly inclined with respect to the strands of the webbing 10 and the same advantages will be found as in the Figure 1 construction.

Having thus described my invention in such full, clear, and exact terms that its construction and operation will be readily understood by others skilled in the art to which it pertains, what I claim as new and desire to secure by Letters Patent of the United States is:

1. A support for comb cleaning webs having transversely arranged loops at the opposite extremities thereof, said support being in the form of a single piece of wire looped upon itself to provide a handle member, one portion of said wire projecting first forwardly from said handle member and then upwardly and laterally and terminating in a transverse holding member at right angles to said handle member, the other portion of said wire projecting upwardly and rearwardly from said handle member and terminating in a second holding member parallel to the first said holding member, the arrangement being such that said two holding members may be sprung toward each other and passed through the respective loops of the web and released to hold the web under tension.

2. A comb cleaner, comprising a stranded web having loops at the opposite ends thereof, and a pair of spaced integrally connected holding members each having a transverse arm adapted to be threaded through the adjacent loop of the web, said arms being biased outwardly at their free ends to yieldingly hold the web taut.

3. A comb cleaner comprising a stranded web having loops at the opposite ends thereof, and a single length of wire returned upon itself at an intermediate point to provide a handle, one end portion of the wire being of greater length than the other and both extremities of the wire being turned upwardly at spaced points and bent crosswise in opposite directions relatively to the axis of the handle to provide spaced apart yieldable arms adapted to be threaded through the loops of the web and maintain the latter taut.

In testimony whereof I affix my signature.

NELL FULTON.
